UNITED STATES PATENT OFFICE.

WILLIAM J. A. LONDON, OF LYNN, MASSACHUSETTS, AND HENRY R. TROTTER, OF WINDSOR, CONNECTICUT.

FAN AND PROPELLER.

1,263,909.

Specification of Letters Patent. Patented Apr. 23, 1918.

Application filed October 3, 1916. Serial No. 123,467.

To all whom it may concern:

Be it known that we, WILLIAM J. A. LONDON, a citizen of Great Britain, residing at Lynn, Massachusetts, and HENRY R. TROTTER, a citizen of Great Britain, residing at 5 Windsor, Connecticut, have invented a new and useful Improvement in Fans and Propellers, of which the following is a specification.

10 This invention relates to the manufacture of the blades of high-speed ventilating and draft fans and air propellers.

15 The object of the invention is to by simple means reduce the sound caused by the revolution of the blades of high-speed fans and propellers, and at the same time so stiffen the blades that they may be made of light material and yet withstand the heavy strains to which they are subjected when 20 driven at high speed.

25 This object is simply attained by setting the leading edges, or edges on the intake or front side of the blades of fans and air propellers, into rounded tubes or rods which engage the inrushing air without the disturbance or shock incident to thin sharp edges and which stiffen the blades so that when made thin they will not break or collapse. These features are of particular 30 advantage in fans designed to rotate at, say, 2,000 revolutions per minute, when used on destroyers and the like vessels in ventilating and furnace draft systems where the elimination of noise and reduction in weight is 35 exceedingly desirable.

40 The invention is illustrated and described herein as embodied in a high-speed multiple-blade vertical-shaft turbine-driven ventilating fan. Figure 1 shows a plan of a form of such a fan. Fig. 2 shows a diametric section. Fig. 3 shows a bottom view of the same. Fig. 4 shows on larger scale a perspective view of one of the blades of such a fan.

45 Projecting from the hub 1 of the fan illustrated is a base cone or shell 2. The outer conical shell 3 and the intermediate conical shell 4 (and there may be any desired number of intermediate shells) are fastened to 50 the base shell by tubes or rods 5—tubes being shown in the drawings. These tubes, of which there will be the same number as it is designed to have blades, may be headed over at the ends so as to fasten them to the

base shell and outer shell, and between the 55 shells the tubes are provided with longitudinal slots. The inner edges of the blades 6 are inserted into the tubes through the slots and are fastened thereto. The side edges of the blades are turned out to form flanges 7 60 by means of which they may be riveted to the shells.

The slotted tubes form light and strong supports for the shells, which turn the air outward in the necessary direction to obtain 65 the greatest efficiency with the least amount of air friction and eddy currents, and the slotted tubes, while light and stiff, form rigid supports to which the leading edges of the blades may be easily secured, and 70 when the blades are thus supported they are so reinforced that they may be made of very thin and light material without danger of breaking. Furthermore, and what is of particular advantage in this construction, is 75 that while forming light rigid supports for the shells and simple reinforcements for the edges of the blades, the rounded tubes so engage and influence the course of the inrushing air that the noise usually incident 80 to the operation of these fans is very materially reduced, which is of great advantage in high-speed fans and propellers which are used in places where it is essential 85 to have the fan run as quietly as possible.

The invention claimed is:

1. A fan or propeller having a hub, slotted supports mounted on the hub, and blades with their leading edges secured in 90 the slots of said supports.

2. A fan or propeller having a hub, slotted tubes mounted on the hub, and blades having their leading edges inserted through 95 said slots and secured in said tubes.

3. A fan or propeller having a hub, conical shells carried by the hub, slotted tubes connecting the shells, and blades with their leading edges inserted through the 100 slots into the tubes and their side edges secured to the shells.

4. A fan or propeller blade comprising a thin wing, and a circular slotted reinforcement fitted onto the leading edge of said wing.

WILLIAM J. A. LONDON.
HENRY R. TROTTER.
